BASIN-FORMING ATTACHMENT FOR
DISK PLOWSAlan G. Muirhead, Pittsworth, Queensland,
AustraliaApplication October 27, 1947, Serial No. 782,417
In Australia June 19, 1945Section 1, Public Law 690, August 8, 1946
Patent expires June 19, 1965

2 Claims. (Cl. 55—30)

1

The object of this invention is to provide means whereby the soil, loosened by a multi-disc cultivator plow, upon a hill-side, or sloping piece of ground, may be simultaneously formed into basins or pockets, for the purpose of holding rain-water and preventing a downpour of rain from running away and being lost, thus conserving moisture in the soil. Another object is to provide means whereby the soil may be formed so that the rain will remain where it falls and prevent erosion on hilly or sloping land.

The nature of the invention will be fully understood from the following description taken in connection with the accompanying drawings wherein:

Figure 1 is a plan of apparatus embodying the invention, said apparatus being shown in relation to the relevant parts of a well known twin-disc plow;

Figure 2 is a detail view of a modified disc;

Figure 3 is a detail view of the means for locking two sliding tubular members of a stay together; and

Figures 4 and 5 are detail views of fastening means.

The invention may be applied to standard multi-disc plows preferably having the series of discs in pairs, and according to the invention a square shaft 10 has upon it a series of modified discs or cutters 11 held at the correct distance apart thereon by spacers such as short lengths of piping. These modified discs 11 may be secured to said shaft 10 by the usual disc bearing bosses 12 which are distanced by the spacers. The square shaft 10 is rounded and threaded at the left hand end and is provided with a retaining pin at the opposite end. Two lock nuts, when tightened up, clamp the modified discs 11, bearing bosses 12, spacers 42 and bearing dust excluders 41 together, so giving added strength and rigidity to the assembly. As an example, it has been found that a fourteen disc plow would require four modified discs 11, and a ten disc plow would require three modified discs 11. The said square shaft 10 is therefore of a length to accommodate the required number of modified discs 11 and is held in end bearings 13 and 14. The right hand bearing 13 is carried at the end of a bar 15 of angle, channel, tubular or other suitable section, the other end of said bar 15 being secured to the column 16 of the front wheel-axle of the plow. This bar 15 is fitted at its rear end to bracket 26, attached to right hand bearing 13. The left hand end of the said square shaft 10 is ahead of the right hand end thereof, and

whereas the latter is approximately at the rear of the right hand twin-disc, the former is approximately behind the twin-disc second from the other end.

The frame 17 of the twin-disc plow (which projects forwardly to the right hand side) and the square shaft 10 of the modified discs 11 are at an angle of approximately 80°. The greater the angle the larger are the basins formed and vice versa. The left hand end of the modified disc shaft 10 is not rigidly connected to the plow framework 17, but by chain 18 and rod 19 or the like, and is not carried by wheels but by the modified discs 11. One chain or rod 19 extends from the rear of the plow framework, to the end of the left hand end of shaft 10, and takes the side draught of the shaft 10, the other chain 18 extending from a bracket 18a equipped with a ramshorn or spiral hook on the framework 17 above and between the third and fourth pairs of twin-discs to a point at the front of the boss 12 of the said disc 11 and takes the forward draught of the left hand end of the shaft 10.

The said discs or cutters 11 may be modified in several ways, one being to use only half a disc, another to use opposed sectors (see Figure 2) each being approximately one quarter of the disc 11. These modified discs are mounted upon their square shaft 10 so that the sectors are alternately at right angles to one another; or if semi-circles are used, they are mounted alternately at 180° to one another.

As shown in the drawings, the rod 15 consists of two tubes or round section rods whose ends overlap and are held in parallel by sleeves 20. Each tube 15 has one of the sleeves 20 rigidly held by a bolt or rivet 21 near its end. This prevents the sleeves 20 from moving and jambing the tubes 15 while they are being adjusted by sliding them through the sleeves 20.

Right angled levers 22 have one of their ends threaded and pointed and adapted to pass through threaded bosses 23 so that the points 24 will wedge themselves between tubes 15 and hold the tubes 15 securely in said sleeves 20. By these means the distance between the right hand end of shaft 10 and the post 16 may be made variable. It will be understood that the draught of the right hand end of square shaft 10 tends to lengthen rods 15 and slide them through sleeves 20. Should this occur, a clockwise rolling motion is imparted to the tapered pins 24 by the rods 15, so automatically screwing tapered points 24 of right angled lever 22 further through threaded boss 23, and jambing pipes 15 tighter in sleeves

20. In other cases where both tension and compression loads may occur, sleeves 20 may be arranged so that one will tend to tighten from the tension loads and the other from the compression loads. This is achieved by arranging sleeves 20 so that their right angled levers 24 are on opposite sides of the pipes 15 to each other. The forward end of this composite rod 15 is secured to said post 16 by an U-bolt and plate, which with a D-shackle forms an universal joint, or other like fastening 25. The rear end of the said composite rod 15 is secured to the bearing 13 at the end of shaft 10 by an angular bracket 26 and a spring loaded pin 27 (see Figure 4). The bracket 26 (see Figure 1) is secured to said bearing 13 by bolts 28 and the free end is flattened and provided with a hole.

Each said pin 27 at its upper end has a handle 29, and the pin 27 passes through a hole in a right angled bracket 30 upon a base 31 which is bifurcated at 32 to accommodate the flattened end of bracket 26. A compression spring 33 around pin 27 is held between bracket 30 and base 31. In connecting the end of rod 15 to shaft 10, the flattened end of bracket 26 is placed in the bifurcated end of base 31, whilst the pin 27 is in an upward position. When allowed to descend the pin 27 passes down through the holes in the bifurcated end of the base 31 and the hole in the flattened end of bracket 26. As shown in Figure 1, a base 31 is attached to the end of rod 15, and a base 31 is attached to rod 19, the pin 27 passing through a hole in the yoke 34.

A suitable quick acting safety hook for connecting the chain 18 to the yoke 34 is shown in detail in Figure 5 and consists of a bar 35 of J-shape with a bar 36 pivotally connected at 37 towards its outer end to the bent end 38 so that when the chain 18 (which is attached in hole 39 of bar 36) is taut, the said bar 36 will be approximately in line with the shorter section of the J-bar 35 with their ends closely adjacent. This is achieved by bar 36 being bent between pivot hole 37 and draught chain hole 39, in the opposite direction to the hook on the J-piece. Thus when the draught chain 18 is taut, the right angled stop 40 on the bar 36 is forced hard against the J-piece 35. The pivot at 37 may consist of a bolt with a spring washer under its head at one side, and lock nuts, or a castle nut and cotter pin on the other side. The hinge may thus be adjusted so that it is just possible to open the hook with the hands. This feature prevents possible unhooking if the draught chain should slacken.

In use the multi-disc plow is drawn along and cultivates the soil in the usual manner. The modified discs 11 (sometimes known as basin lister attachments) are rotated in unison by their square shaft 10. Whilst the rearmost modified disc 11 and every second one from it is in the ground they are forming a depression and lifting the soil to one side. Simultaneously the alternate modified discs 11 are being carried above the soil and allowing a hill to remain. With each half rotation of the shaft 10 semi-circular attachments would be forming one depression and one hill in line across, so that when the shaft 10 has revolved many times there will be a depression between four hills and vice versa; in other words the field will be checkered with hills and depressions, in which depressions the rain is held and prevented from running or flowing downhill. This rain is enabled to soak the soil and subsoil and much moisture is thereby con-

served; in addition to which erosion is prevented. Soil fallowed in this manner is greatly improved and better growth is subsequently promoted.

When two sectors of a disc 11 are used there will be four lines ahead formed with each rotation of the disc 11; and it will be understood that other modifications of the discs 11 or cutters may be used whilst accomplishing the purposes of the invention. For example, it will be found that satisfactory results will be obtained with twin-modified-discs. The spacing of the modified discs 11 or cutters should be such that there will not be channels or gaps between the depressions, and the modified discs 11 or cutters should be so disposed as to throw the soil in an opposite direction to the soil thrown by the discs upon the plow. Thus the side draught set up by the modified discs 11 assists the plow in its work by countering the side draught of the plow.

There are two convenient methods of transporting this basin lister attachment in conjunction with its plow. The first and easiest for transporting from one field to another, over comparatively smooth land, is by means of adjusting the length of the tubes 15, so that the square shaft 10 is at a right angle to the line of advance of the plow. This permits the modified discs to assume the purpose of wheels and roll over the ground without cutting into it. The side draught rod 19 then serves a dual purpose in preventing the square shaft 10 from creeping to either side, thus ensuring that it runs straight behind the plow. The attachment cannot run up on to the plow when descending hills because it is held back on the right hand side by tubular rods 15, and if the left hand side tends to run up, the square shaft 10 tends to resume its working position and the modified discs 11 cut into the soil and are arrested.

In the second transporting method for longer journeys over rougher ground, the two spring loaded plungers 27 and hook 35 are released. Rods 15 and 19 are hinged up on to the frame of the plow, and chain 18 also stowed on the plow frame. Square shaft 10, complete with modified discs 11, is then lifted and laid along on top of the line of plow discs and parallel with this line. Two short chains 43 then secure the assembly to the frame of the plow. These chains 43 are permanently attached to the frame of the plow for this purpose.

I claim:

1. Improved means for cultivating sloping ground, comprising a shaft for rotatable attachment by draught means to the rear of a multi-disc plow, a series of modified discs fixed to and spaced along said shaft, so that alternate modified discs alternately form hills and those between form valleys upon rotation of the shaft behind the moving plow, said shaft being set at an angle to the furrows formed by said plow such that the side draught set up by the modified discs will counteract the side draught of the plow, a multi-part sectional draught rod connecting one end of the plow with one end of the shaft, adjustable means connecting the sections of said draught rod to increase or decrease the length thereof to adjust the angle of the shaft with respect to the plow, a laterally extending means fixed to the opposite end of the plow adjacent the respective opposite end of the shaft, a plurality of draught means connecting said opposite end of the shaft to the plow, one of said draught means being rigid and fastened at one end to said laterally extending means, another

of said draught lines being flexible and fastened at one end to an intermediate point between the opposite ends of said plow, and common means for connecting the opposite ends of said plurality of draught means to the adjacent end of the shaft.

2. The improved means for cultivating sloping ground as set forth in claim 1, in which the ends of the plurality of draught means are adjustably connected to the common attaching means.
